TERRARIUM PLANTING TOOL

Dell A. Budreau, Cedar Falls, Iowa, assignor to Terra
Thumb, Inc., Cedar Falls, Iowa

Filed May 4, 1973, Ser. No. 357,449

Term of patent 14 years

Int. Cl. D8—05

U.S. Cl. D8—51

FIG. 1 is a front perspective view of the terrarium planting tool of my new design;

FIG. 2 is an enlarged front view;

FIG. 3 is a side view;

FIG. 4 is a top plan view; and

FIG. 5 is a bottom plan view.

The broken lines representing the terrarium are shown for illustrative purposes only.

I claim:

The ornamental design for a terrarium planting tool, substantially as shown and described.
